UNITED STATES PATENT OFFICE.

FRANK E. ORMSBY, OF CHICAGO, ILLINOIS.

WASHING MACHINE.

1,419,300.

Specification of Letters Patent. Patented June 13, 1922.

Application filed July 21, 1921. Serial No. 436,433.

To all whom it may concern:

Be it known that I, FRANK E. ORMSBY, a citizen of the United States, residing at Chicago, in the county of Cook and State 5 of Illinois, have invented certain new and useful Improvements in Washing Machines, of which the following is a description.

My invention relates to improvements in washing machines and has among its objects 10 the production of a device of the kind described which is simple, compact, reliable, efficient and satisfactory for use wherever found applicable.

One of the objects of my invention is 15 to provide a washing machine having a drum of a special shape which may be operated to describe a rocking movement similar to that of a rocking chair rolling back and forth on a horizontal plane or base. This 20 action tends to give a uniform and efficient movement of the water or other liquid within the tub so as to effectively wash the garments placed therein, necessitating a minimum amount of driving mechanism or 25 power. The load is practically balanced due to the shape of the drum so that there is a tendency to automatically restore the load to equilibrium when the driving power ceases.

30 Another object of my invention is to provide pockets or chambers at opposite ends of the drum, said pockets being so formed that a pressure is produced therein at one direction of movement of the drum, thereby 35 forcing air and water through the garments, and upon the opposite direction of movement of the drum, a suction is formed thereat, drawing air and water from the pocket through the garments.

40 Another object of my invention is to provide deflector or baffle means on the drum at the bottom thereof which will cause the garments being washed to be turned or changed constantly, thus causing all portions 45 of the load to come in contact with the liquid and the pockets, said means also producing a spiral movement of the liquid within the drum.

Many other objects and advantages of the 50 construction herein shown and described will be obvious to those skilled in the art from the disclosure herein given.

To this end my invention consists in the novel construction, arrangement and com-

bination of parts herein shown and described, and more particularly pointed out in the claims.

In the drawings, wherein like reference characters indicate like or corresponding parts,

Fig. 1 is a side elevation of my device;

Fig. 2 is a rear end elevation thereof;

Fig. 3 is a vertical section through the drum;

Fig. 4 is a section taken substantially on 65 the line 4—4 of Fig. 1;

Fig. 5 is a section taken substantially on the line 5—5 of Fig. 6;

Fig. 6 is a section taken substantially on 70 the line 6—6 of Fig. 5, and

Fig. 7 is a section taken substantially on the line 7—7 of Fig. 1.

In the drawings, wherein I have illustrated the preferred embodiment of my invention, 1 indicates the supporting frame of 75 a machine having a driving mechanism near its bottom enclosed by a housing 2 and upon which is detachably mounted a drum or operating tub 3. The tub or drum 3 is constructed of any suitable material, and is 80 preferably in the form of an oval in vertical cross-section, as shown, the top and bottom parts preferably being constructed on true circles drawn from center line points at either edge so as to secure the proper roll or 85 rocking movement. Projecting beyond the opposite sides 4 of the tub 3 centrally of the ends thereof are pins or rollers 5, said pins or rollers being adapted to freely engage in slotted openings 6 provided in the brackets 7 arranged at the opposite sides of the supporting frame 1, said brackets 7 having a track portion extending substantially in a horizontal plane so as to form a horizontal 90 or flat bearing plate upon which the curved bottom of the tub is adapted to slide or rock. If desired, a strip of asbestos or other suitable material 8 is positioned between the tub and the bracket so as to eliminate noise 95 therebetween.

Pivotedly attached to one end of the tub 3 is a pitman or connecting rod 9, said pitman being preferably longitudinally yieldable and comprising two telescopic portions 10 and 11 with a resilient spring 12 therebetween, as shown in Figure 7. The lower end of said pitman is connected to a crank 13 driven in any suitable manner, as by an

electric motor or the like, positioned within the housing 2. A cover plate 14 of a suitable size is arranged on the upper surface of the drum for the insertion and removal of the 5 material to be acted upon. Arranged at opposite ends of the drum, as shown more clearly in Figures 3 and 4 are one or more vanes 15, said vanes being curved so as to form substantially curved, tapered pockets 10 16 opening toward the bottom of the drum. The free edges of said vanes are below the center of the tub and preferably about half way up from the bottom thereof. On the inside of the tub is arranged a baffle or deflecting rib or projection 17 extending from side to side along the bottom thereof, obliquely or diagonally in a direction thereacross, said rib decreasingly tapering from its midpoint to both its ends and to opposite sides of its 15 base so that a transverse cross-section through said rib would be shaped substantially triangular, as shown in Figure 3.

The rotation of the crank 13 will operate the pitman 9 to cause the drum to rock or 20 tilt on the horizontally extending bearing portions or tracks of the brackets 7, the pins 5 being free in the slots 6 and serving merely to limit and guide the tub in its rocking movement. The telescopic action of the pit- 25 man parts and the free insertion and removal of the pins 5 into the slots 6 permits the tub to be readily lifted from the frame whenever it is desired to do so, as for instance for the purpose of cleaning, repairing, 30 shipping, etc.

In operation, assuming that the tub 3 has water or other suitable liquid therein and is loaded to the proper height, the rocking movement thereof will cause the liquid there- 40 in to follow a path somewhat as indicated diagrammatically in dotted lines in Figures 3 and 4, the body of water splitting at the free ends of the vanes, as shown, a portion of it following the outer surface of the vanes 45 and forming substantially a figure 8, while the other portion of the water tends to move into the pockets 16 thereby causing the air in the pockets to be compressed by the water. The movement of the last mentioned water 50 is substantially as shown in Figure 4; that is, it moves in a curved path in a continuous direction without reversal along the sides and ends of the drum. This is caused by the diagonal rib 17 sloping from the 55 center towards both ends whereby a larger proportion of the water at the ends of the drum is to one side of the longitudinal center line of the drum, and as these areas of majority water supply are diagonally ar- 60 ranged, the direction of the flow of the water will be governed accordingly and will be in a curved path about the ends and sides of the drum in a continuous direction as shown. The material is plunged against the pockets 65 toward which liquid is flowing, so that a

"cupping" action is produced, whereby the liquid will be forced through the material at the pockets and into the pockets to compress the air therein. The successive or alternate rocking movement of the tub releases 70 the liquid from the pocket and at the same time produces a partial suction or decrease in air pressure therein, so that the air and liquid from the pocket is drawn or sucked through the load. The creating of an air 75 pressure and a partial vacuum or suction in the opposed pockets 16 alternates upon each rocking movement of the tub. The oscillating motion of the tub as it rocks to and fro plunges the load against the ends of the vanes 80 where the pockets are arranged, holding them there while the air and liquid is driven therethrough. This action may be called a "cupping" action because the material is held over the pocket while the liquid and air 85 is forced therethrough into the pocket.

If desired, handles 18 are arranged at opposite ends of the tub, whereby the tub may be lifted from the frame, or, if desired, the tub may be manually rocked. A drain 90 19 may be arranged adjacent the bottom of the tub, as shown. In case it is desired to heat the water in the tub after it has been placed in position on the frame 1, a burner or jet 20 may be arranged beneath the tub. 95

With the hand-operated machine, there would, of course, be no drive housing at the bottom of the frame, so that the removable drum could be placed therein when being crated and shipped, thus saving considerable 100 lumber, labor and car storage space.

The device may be used satisfactorily as a churn, if desired, and without any change in the construction thereof, resulting in an efficient and sanitary churn, or for any kind 105 of extracting or mixing purposes, inasmuch as the smooth interior of the drum may be easily cleaned, and my description and claims have in mind such a use.

Having thus described my invention, it is 110 obvious that various immaterial modifications may be made in the same without departing from the spirit of my invention; hence I do not wish to be understood as limiting myself to the exact form arrangement, 115 construction and combination of parts herein shown and described, or uses mentioned.

What I desire to secure by Letters Patent of the United States is:

1. In a device of the kind described and 120 in combination, a frame, a drum oval in vertical longitudinal cross-section arranged thereon, means dividing said drum into different zones, means for operating said drum so that it rocks to and fro in a vertical plane 125 in said frame whereby a portion of the liquid therein moves in a vertical plane in the form of a figure 8 in one of said zones, and means in the other zone for moving another portion of the water therein in a con- 130

tinuous direction about the sides and ends of the drum transverse to said figure 8.

2. In a device of the kind described and in combination, a frame, a drum arranged therein, said drum being oval in vertical longitudinal cross-section, tapering pockets in said drum at each end thereof, said pockets being curved to merge into the ovally curved inside surface of the drum, and means for 10 rocking said drum in a vertical plane in said frame, whereby the rocking movement of the liquid therein will alternately cause a pressure of air and liquid and then a suction to be built up in said pockets, whereby 15 said air and liquid is alternately forced through and drawn through said garments at said pockets.

3. In a device of the kind described and in combination, a frame, an oval drum arranged thereon, pockets in said drum at the ends thereof, and means for rocking said drum in a vertical plane in said frame, whereby the liquid in the drum is forced into and compresses the air in said pockets 25 on one stroke, and escapes therefrom to form a suction threat on the next stroke, each of said pockets formed with a sheet of material curved so as to merge into the curved inside surface of the drum.

30 4. In a device of the kind described and in combination, a frame, a drum arranged thereon, means for rocking said drum in a vertical plane on said frame, and means for turning the load in said drum on each of 35 said rocking strokes, said means comprising a rib projecting upwardly from the inner surface of said drum and extending substantially in a diagonal direction thereacross, and decreasingly tapering in both directions

from the mid-point thereof to the ends and 40 to its sides.

5. In a device of the kind described and in combination, a frame and a drum arranged thereon, said drum being oval in longitudinal vertical cross-section, a pair of 45 pockets therein at the ends thereof, a rib on the inner surface of the bottom of said drum extending in a diagonal direction thereacross, and decreasing in height from the mid-point to both ends and both sides 50 thereof, and means for rocking said drum in a vertical plane in said frame, whereby a portion of the fluid in said drum will describe substantially the path of a figure 8.

6. In a device of the kind described and in combination, a frame and a drum arranged thereon, said drum being oval in longitudinal vertical cross-section, and provided with a pair of pockets therein at the ends thereof, a rib on the inner surface of the 60 bottom of said drum extending in a diagonal direction therein, and decreasing in height from the mid-point to both ends and both sides thereof, and means for rocking said drum in a vertical plane in said frame, 65 whereby the liquid in said drum will describe substantially the path of a figure 8. a portion of said liquid being alternately forced into and discharged from said pockets to alternately create a pressure and a suction 70 thereof.

In testimony whereof, I have hereunto signed my name in the presence of two subscribing witnesses.

FRANK E. ORMSBY.
